TRYGVE JOLSTAD, OF DETROIT, MICHIGAN, ASSIGNOR TO MICHIGAN STAMPING COMPANY, OF DETROIT, MICHIGAN, A CORPORATION OF MICHIGAN.

STRETCHING DIE FOR SHEET METAL.

Application filed May 7, 1923. Serial No. 637,371.

This invention relates to dies for stretching and shaping sheet metal.

An object of the invention is to provide a simple and effective device for holding the metal so that it will not slip while it is being shaped to the desired form.

Another object is to provide reliable and practical means for clamping the jaws upon the metal while at the same time permitting the jaws to slide during the operation of the die.

Another object is to provide means for normally retaining the jaws in retracted position and for regulating the sliding movement thereof whereby the metal will be shaped properly by the die.

With the above and other objects in view, the invention consists of certain novel features of construction, combinations and arrangements of parts as will be more fully described and particularly pointed out in the appended claims;

In the accompanying drawings:—

Fig. 1 is a fragmentary front elevation of a press and showing parts in section;

Fig. 2 is a perspective view of the bed plate and supporting frame for the jaws;

Fig. 3 is a sectional view taken on line 2—2 of Fig. 2;

Fig. 4 is an enlarged vertical sectional view through the bed-plate, frames and die and showing the jaws in elevation; and

Figs. 5, 6, and 7 are views similar to Fig. 4 but showing a slightly modified construction.

With certain constructions now in use, a reciprocating holder is employed to clamp the sheet metal directly upon the bed plate so that the metal is permitted to slide over the edges surrounding the central opening in the bed plate when the die is operated to shape the metal. However, it has been found that the metal very often slips while being shaped with the die with the result that the metal is shaped improperly. It has also been found that it is necessary to provide relatively wide sheets of metal so that there will be sufficient bearing surfaces at the edges thereof for engagement with the bed plate to prevent the metal from being pressed entirely through the opening therein when the die is operated. Furthermore, such constructions are objectionable for the reason that after the metal has been shaped, the

portions providing bearing surfaces have to be cut off and scrapped.

With the present invention all of the objectionable features just referred to are entirely overcome and all of the desired results are accomplished with the use of less material. In detail, the numeral 1 designates a suitable base supporting a bed plate 2 which is preferably provided with a central opening 3 and an integral horizontal frame 4 to receive the die or plunger 5 for stretching the metal. This die may be any shape desired and any suitable means may be employed for actuating the same.

The sheet of metal to be shaped is preferably held in proper position over the frame 4 by means of a plurality of sets of complementary elongated jaws 6 and 7 which are provided with teeth 8 that grip the metal at its opposite edges. The jaws 6 of each set may be mounted on any two of the side bars 9 of the frame and preferably extend longitudinally thereof while the complementary co-operating jaws 7 of each set are preferably provided with rearwardly extending lugs 10 that are mounted on horizontal pivots 11 extending through spaced lugs 12 on the jaws 6. The jaws 6 are adapted to slide over spaced parallel elongated transversely extending recesses 13 in the upper surface of the side bars of the frame and are preferably provided with laterally extending ribs 14 that engage inverted substantially L-shaped guides 15 detachably secured to the frame 4, while the jaws 7 are normally held in raised position with respect to the jaws 6 by means of coil springs 16 engaging recesses in the opposed faces of the jaws. Yokes 17 extend downwardly from rearward extensions 18 on the jaws 6 and embrace spools 19 that are slidably mounted on bolts 20 extending longitudinally of the recesses 13 in the frame. Coil springs 21 surround the bolts between the spools and the inner ends of the recesses 13 and normally retain the jaws spaced from the inner edges of the frame 4.

Any suitable means may be employed for clamping the pivoted jaws 7 upon the metal and for holding the said jaws in clamped position during the operation of the die, while at the same time permitting the jaws 6 and 7 to slide inwardly. As shown, a vertically movable horizontal frame 22 sur-

rounds the die and is adapted to move the pivoted jaws 7 downwardly against the tension of the springs 16 to clamp the metal upon the jaws 6. The frame 22 may be actuated by any suitable means (not shown) and the movement thereof is preferably timed with relation to the die 5 so that the frame 22 will clamp the pivoted jaws 7 upon the metal before the die is moved downward. 10 Likewise the die may be moved upwardly in advance of the frame 22.

In use, a sheet of metal may be placed upon the jaws 6 and the frame 22 may be moved downwardly to clamp the jaws 7 upon the metal. The die may then be lowered to shape the metal and during the shaping operation, the metal will be pressed downwardly as shown in Figure 4 which will cause the jaws to slide inwardly between the frames 4 and 22. When the die is raised the springs 16 will raise the upper jaws 7 and the springs 21 will return both the jaws 6 and 7 to normal retracted position. 20

In the modification illustrated in Figure 5, a slightly different form of frame 30 is used. The bars 31 of this frame preferably incline inwardly and are formed integral with vertical extensions 32 upon the bed plate 33. A die 34, operable in a manner similar to the die 5, is used in this construction and is adapted to move downwardly between the frame 30 and the extensions 32 upon the bed plate to stretch the metal to the desired shape. The metal to be shaped 30 is adapted to be gripped at its opposite edges by means of jaws 35 which are slidably mounted on the bars 31 of the frame in a manner similar to the jaws 6 while jaws 36 are pivoted upon the jaws 35 in a manner similar to the jaws 7 and are normally spaced therefrom by means of coil springs 37. The jaws 36 are adapted to be clamped upon the metal by means of a frame 38 which is provided with inclined 40 portions 39 for engagement with the jaws 36 and which is movable vertically similar to the frame 22. The inner ends of both the jaws 35 and 36 are inclined as shown at 40 and 41 respectively so that they will be 50 in alignment with their sides 42 of the extensions 32 when the jaws are moved inwardly. Coil springs 43 are located in the recesses 44 in the frame bars supporting the jaws and engage depending lugs 45 upon the jaws 35 to normally retain the same in spaced relation to the inner edges of the frame 30.

In the modification illustrated in Figure 6, the die 50 is preferably stationary and 60 is mounted upon a bed plate 51 which is supported upon channel members 52 that are secured to a suitable base 53. The frame 54 for supporting the jaws 55 and 56 surrounds the die 50 and is movable vertically 65 with respect to the bed plate. The jaws 55

are slidably mounted on the frame in a manner similar to the jaws 6 and are similar in construction, while the jaws 56 are pivoted upon the jaws 55 in a manner similar to the jaws 7 and are normally spaced from the jaws 55 by means of coil springs 57. 70

A plurality of arms 58 are secured to the frame 54 and extend downwardly through openings 59 and 60 respectively in the flanges 61 of the die and in the bed plate. 75 These arms are connected at their lower ends to a plate 62 which is located beneath the bed plate 51 and between the channel members. Coil springs 63 are located between the base 53 and the plate 62 and normally 80 retain the latter in engagement with the bed plate. The jaws 56 are adapted to be clamped upon the metal by means of a frame 64 which is also adapted to move the jaws 55 and 56 as well as the frame 54 85 downwardly against the tension of the springs 63 toward the bed plate so that the metal clamped by the jaws will be forced over the die and will be shaped accordingly. Any suitable means (not shown) may be 90 employed for operating the frame 64.

In the modification illustrated in Figure 7, a construction is shown for stretching a sheet of metal so as to remove all crimps and uneven surfaces preliminary to shaping the same. In detail, a horizontal frame 70 similar in construction to the frame 4 is formed integral with a bed plate 71 which is similar in construction to the bed plate 2. Jaws 72 are slidably mounted on the frame 70 in 100 a manner similar to the jaws 6 and are preferably similar in construction, while cooperating jaws 73 are pivoted upon the jaws 72 and are preferably similar in construction to the jaws 7. The jaws 73 are adapted 105 to be clamped upon the metal at the edges thereof by means of a frame 74 which may be moved vertically by any suitable means (not shown).

The jaws 72 and 73 are adapted to be 110 moved outwardly to stretch the metal and for this purpose I preferably provide substantially L-shaped fingers 75 which are detachably secured to a vertically movable frame 76 and which are provided with 115 inclined outer surfaces 77 at their lower ends for engagement with the outer walls of vertical openings 78 in horizontal arms 79 extending rearwardly from the jaws 72 intermediate the ends thereof. Any suitable means (not shown) may be employed for moving the frame 76 and fingers downwardly to cause both of the jaws 72 and 73 to be moved outwardly so that the sheet of metal clamped thereby will be stretched. 120

While it is believed that from the foregoing description, the nature and advantages of the invention will be readily apparent, I desire to have it understood that I do not limit myself to what is herein shown and 125 130

described and that such changes may be resorted to when desired as fall within the scope of what is claimed.

What I claim as my invention is:—

- 5 1. In a device of the class described, a plurality of opposed slidably mounted jaws for clamping the metal to be stretched, a support for said jaws, means for actuating one of said jaws to clamp the metal while at the same time permitting said jaws to move upon said support with the metal in a direction substantially transverse to the direction of stretching of the metal and means carried by said support for regulating the sliding movement of said jaws.
2. In a device of the class described, a plurality of co-operating jaws for holding the metal to be shaped therebetween, a frame supporting said jaws; means for actuating one of said jaws to clamp said metal before it is shaped while at the same time permitting the lower jaws of each set to slide upon said frame in a direction substantially transverse to that of shaping of the material when said metal is being shaped, and means for normally retaining the jaws of each set in spaced relation to the inner edges of said frame and for regulating the sliding movement of said jaws.
3. In a device of the class described, a plurality of opposed slidably mounted jaws for supporting the metal to be stretched, pivotally mounted jaws adapted to cooperate with the slidably mounted jaws for holding the metal, yieldable means for normally retaining the last-mentioned jaws in spaced relation to the first-mentioned jaws, means for clamping the pivotally mounted jaws upon the metal, a die, and means for relatively moving the die and sheet metal for shaping the metal.
4. In a device of the class described, opposed slidably mounted jaws for supporting the metal to be stretched, pivotally mounted jaws adapted to cooperate with the jaws aforesaid to clamp the metal, yieldable means disposed between the jaws aforesaid for normally retaining the pivotally mounted jaws in raised position, reciprocatory means for clamping the pivoted jaws upon the metal, a die, and means for shaping the metal about the die.
5. In a device of the class described, a pair of frames, opposed jaws slidably mounted on one of said frames for supporting the metal to be stretched, jaws pivotally mounted on the jaws aforesaid and adapted to cooperate therewith to clamp the metal, yieldable means for normally retaining the pivoted jaws in raised position, means for moving the other of said frames to clamp the pivoted jaws upon the metal, a die, and means for shaping the metal about the die.
6. In a device of the class described, a frame, opposed jaws slidably mounted upon said frame, guides for said jaws detachably secured to said frame, jaws pivotally mounted on said slidably mounted jaws and adapted to cooperate therewith to clamp the metal, means for normally retaining said pivoted jaws in raised position, means for clamping said pivoted jaws upon said metal, a die and means for shaping the metal about the die.
7. In a press for working sheet metal, the combination with a bed-plate having a central opening, of sets of complementary jaws slidably mounted on said bed-plate at opposite sides of said opening, yieldable means normally separating the complementary jaws of each set, means for closing the jaws of each set, and means for moving the sets of jaws simultaneously on said bed-plate when said jaws are closed.
8. In a press for working sheet metal, the combination with a bed-plate, of means on the bed-plate for holding the sheet metal to be shaped including a plurality of sets of opposed slidably mounted complementary jaws, each set comprising a lower jaw and a cooperating upper jaw, said upper jaw being pivoted upon said lower jaw, and means for clamping said complementary jaws upon the metal before it is shaped.
9. In a press for working sheet metal, the combination with a bed-plate, of movable means on the bed-plate for holding the sheet metal to be shaped including a plurality of sets of complementary jaws, each of said sets comprising a slidably mounted lower jaw and a pivotally mounted upper jaw, and means for moving the pivoted jaws of each set toward said slidably mounted jaws to clamp the metal therebetween before it is shaped.
10. In a device of the class described, a plurality of opposed slidably mounted jaws for holding the metal to be shaped, means for clamping said jaws upon said metal before it is shaped while at the same time permitting said jaws to move with the metal when said metal is being shaped, the direction of movement being substantially transverse to the direction of shaping of the metal, and means for regulating the movement of said jaws.
11. In a device of the class described a pair of jaws pivotally connected to each other for clamping the metal to be stretched, means for normally separating the jaws of said pair, a frame supporting said jaws, means for actuating one of said jaws to clamp the metal before it is stretched while at the same time permitting said jaws to slide upon said frame while securely clamped to the metal, and yieldable means for regulating the sliding movement of said jaws.
12. In a device of the class described, the combination with a substantially horizontal frame for supporting the work, and a substantially vertically movable die for engag-

- ing the work, of means for holding the work including pairs of opposed jaws slidably mounted upon the upper face of said frame, means for maintaining said jaws in engagement with the work during a predetermined movement of the die, and means for automatically releasing the jaws from the work when said die reaches a predetermined position.
- 10 13. In a device of the class described, the combination with a vertically movable die for shaping the work, a substantially horizontal frame having a central opening for receiving the die, and a reciprocating frame 15 above the frame aforesaid, of means for holding the work including reciprocating jaws on said first-mentioned frame movable along lines extending from the outer edges of said frame to the edges of said opening,
- 15 20 and cooperating jaws pivotally mounted upon the reciprocating jaws in such a way as to be moved automatically by the reciprocating frame aforesaid into engagement with the work.
- 20 25 14. In a device of the class described, the combination with a stationary frame and a reciprocating frame, of means for holding the work upon the first-mentioned frame including reciprocating jaws on said first-30 mentioned frame movable along lines extending from the outer edges of said frame toward the center thereof, and cooperating jaws pivotally mounted upon the reciprocating jaws in such a way as to be moved automatically by the reciprocating frame into engagement with the work.
- 25 30 15. In a device of the class described, a frame having an opening at the center thereof for receiving a reciprocating die, means 40 for holding sheet metal to be shaped over said opening including reciprocating jaws on said frame, and cooperating pivotally mounted jaws carried by said reciprocating jaws, yieldable means normally maintaining
- 45 said reciprocating jaws in spaced relation to the edge of said opening, and means for moving the pivotally mounted jaws into engagement with the sheet metal before it is shaped while permitting said reciprocating jaws to move upon said frame toward 50 said opening when said metal is being shaped.
16. In a device of the class described, the combination with a substantially horizontal frame having a vertical opening therein, and 55 a substantially vertically movable reciprocating die movable into said opening, of means for holding the work including reciprocating jaws movable over the upper face of said frame along lines extending 60 from the outer edges of said frame to the edges of said opening.
17. In a device of the class described, a frame having an opening therein for receiving the work while it is being shaped, and 65 means engageable with the work for shaping the same, and means for holding the work including reciprocating jaws movable over the upper face of said frame along lines extending from the outer edges of said frame 70 to the edges of said opening.
18. In a device of the class described, the combination with a substantially horizontal frame having an opening therein for receiving the work while being shaped, and means 75 for shaping the work, of means for holding the work while being shaped including jaws movable over the upper face of said frame along lines extending from the outer edges of said frame to the edges of said opening, 80 and means associated with said shaping means for maintaining said jaws in engagement with the work while the latter is being shaped, said last-mentioned means permitting said jaws to move over said frame along 85 the lines specified while being shaped.

In testimony whereof I affix my signature.
TRYGVE JOLSTAD.
